UNITED STATES PATENT OFFICE.

GERHARDUS CLOWES CARMAN, OF ST. JOHN, NEW BRUNSWICK, CANADA.

SHIPPING-TAG.

No. 911,206.

Specification of Letters Patent.

Patented Feb. 2, 1909.

Application filed March 26, 1908. Serial No. 423,440.

To all whom it may concern:

Be it known that I, GERHARDUS CLOWES CARMAN, a citizen of Canada, residing at St. John, in the Province of New Brunswick, 5 Canada, have invented new and useful Improvements in Shipping-Tags, of which the following is a specification.

My invention pertains to shipping tags; and it contemplates the provision of a shipping tag having simple, permanently attached and strong means through the medium of which it may be quickly and strongly fastened to bales, trunks and other shipping packages.

15 The invention will be fully understood from the following description and claim when the same are read in connection with the drawings, accompanying and forming part of this specification, in which:

20 Figure 1 is a view showing one side of the tag constituting the best practical embodiment of my invention of which I am aware. Fig. 2 is a view showing the opposite side of the tag, and Fig. 3 is a detail section taken 25 in the plane indicated by the line 3—3 of Fig. 2, looking in the direction of the arrows.

Similar letters designate corresponding parts in all of the views of the drawings, referring to which:

30 A is the body of my novel tag which is made of tough paper or other material suitable to the purpose and B is the pin fastener of the tag.

As best shown in Figs. 2 and 3, the body 35 A is provided with an end portion a, and the said end portion is bent back on the major portion of the body and connected thereto in a strong manner through the medium of adhesive or other suitable means.

40 In this way is formed at one end of the body A a barrel b, and in the said barrel is journaled the inner bar c of the before mentioned pin fastener B which, in addition to the said inner bar, comprises an end bar d disposed 45 at a right angle to the inner bar, a fastening pin e which extends from the end bar and rests nearly parallel to the inner bar c, and a guard pin f which extends from the opposite end of the inner bar c, with reference to 50 the end bar d, and is extended at an acute angle from said inner bar until it contacts with the fastening pin e at an intermediate point in the length of the latter.

By virtue of the pin fastener B being 55 constructed as set forth in the foregoing it will be manifest that the fastening pin e

may be readily forced into a bale or analogous device to which the tag is to be attached, and that when the pin e is relieved of pressure, the guard pin f will serve to 60 engage the bale or other device in a reverse direction to the pin e and by so doing will preclude casual withdrawal of pin e and the consequent disconnection of the fastener B from the bale or the like. It will also be 65 manifest in this connection that during the insertion of the fastening pin e in a bale or the like, the guard pin f will give toward the inner bar c of the fastener and hence will not interfere with the pin e being pushed 70 home. When, however, the pin e has been inserted to the extent desired and there is any tendency for said pin to draw out, the guard pin f will operate in the manner and for the purpose before set forth. 75

It will be noted by reference to Fig. 2 that the barrel b of the body A receives the inner bar c of the pin fastener B and rests substantially parallel to the pin e, and extends from the end bar d to the guard pin f. 80 By virtue of this specific relative arrangement of parts it will be manifest that the body A may be used to advantage as a handle or hand grasp through the medium of which the pin e of the pin fastener B 85 may be readily inserted into the bale or other article to which the tag is to be attached; also, that it is expedient to use the body A as a handle incidental to working the pin e and the pin fastener B, as a whole, 90 out of engagement with the bale or other article. It will be further manifest that the specific connection stated between the body A and the pin fastener B is a strong and durable one, and that while the bar c of the 95 pin fastener is free to turn on its axis in the barrel b, any other movement of the pin fastener, relative to the body, is precluded.

Having described my invention, what I claim and desire to secure by Letters-Pat- 100 ent, is:

The herein described shipping tag consisting essentially of a pin fastener, formed of a single piece of material and having an inner, straight bar, of circular form in cross-section, an end bar extending at a right angle from one end of the inner bar, a fastening pin extending in a straight line from the said end bar and disposed substantially parallel to the inner bar, and a guard pin 105 extending at an acute angle from the opposite end of the inner bar and in a reverse 110

direction to the fastening pin and arranged with its point opposed to the side of said fastening pin, in combination with a body having at one end a straight barrel which receives the inner straight bar of the pin fastener and extends from the end bar to the guard pin of said pin fastener, as and for the purpose set forth.

In testimony whereof I have hereunto set my hand in presence of two subscribing witnesses. 10

GERHARDUS CLOWES CARMAN.
